United States Patent

Des. 237,441
Patented Nov. 4, 1975

237,441

TABLE

Leonard V. Birnbaum, Highland Park, Ill., assignor to Burwood Products Company, Chicago, Ill.

Filed July 2, 1973, Ser. No. 375,485

Term of patent 14 years

Int. Cl. D6—03

U.S. Cl. D6—177

FIG. 1 is a perspective view of a table showing my new design;

FIG. 2 is a bottom plan view thereof, drawn to a reduced scale;

FIG. 3 is a front elevational view thereof; and

FIG. 4 is a top plan view thereof.

I claim:

The ornamental design for a table, as shown.
